HEAT-TREATING APPARATUS

Glen C. Riegel and Dale J. Wright, Peoria, Ill.,
assignors to Caterpillar Tractor Co., Peoria, Ill.,
a corporation of California

Application September 26, 1949, Serial No. 117,869

2 Claims. (Cl. 266—4)

1

This invention relates to apparatus for controlling the hardness pattern of an irregularly shaped part during the heat treatment thereof.

In the heat treatment of irregularly shaped parts having relatively thin sections adjacent a larger section, one of the principal problems encountered is that during quenching the thin sections cool more rapidly and harden before the larger masses. As a result, cooling and hardening of the larger masses causes cracking of the already hardened thin sections due to the larger volume of the hardened material. This difficulty is particularly aggravated in automatic equipment for heating and quenching parts of this type in that it has been impractical to achieve selective quenching of the various sections of a single part.

It is, therefore, an object of this invention to provide apparatus for automatically controlling the cooling rate of various sections of an irregularly shaped part. It is another object of this invention to provide apparatus for automatically carrying an irregularly shaped part through a heating cycle and a controlled quenching cycle to produce a selected hardness pattern in the part. Other objects and advantages of this invention will be made apparent in the following specification wherein reference is made to the accompanying drawings.

For purposes of illustration, the invention is shown in its application to the heat treatment of a track link of the type commonly employed in the endless track mechanism of a track-type tractor, however, it will be readily apparent that it may be adapted for use with other parts.

In the drawings:

Fig. 1 is an isometric view of a typical track link;

Fig. 2 is an isometric view of the general arrangement of automatic heat treating apparatus embodying the present invention; and

Fig. 3 is a schematic diagram of a preferred arrangement of the electrical, air, and coolant circuits to accomplish automatic control of the heat treating cycle.

In Fig. 1, a typical track link of the type commonly employed in the endless chain mechanism of a track-type tractor is illustrated generally at 10. One face of the track link is provided with suitable apertures 11 for the reception of bolts (not shown) for securing track shoes to the link while the opposite face is provided with a rail surface comprising a central portion 12, of full rail width, and end portions 13 and 14 of less than full rail width. A transverse bore 15

2

is provided adjacent each end of the link for the reception of hinge pins (not shown) connecting the link with similar links to form an endless chain mechanism having a continuous rail surface upon which the weight bearing rollers of the vehicle may roll. The end portions 13 and 14 terminate in generally convex surfaces 17 and 18 respectively, which are adapted to cooperate with concave surfaces 19 and 20 underlying the full width rail portion 12 to form a self cleaning rail joint.

Due to the abrasive environment in which the track mechanism must operate, it is desirable that the rail surface of the track link be hardened to increase its life. In the past, this has been accomplished by heating the rail surface above the critical temperature of the material and then quenching the part to produce a rail surface of substantially uniform hardness. In a track link hardened in this manner, the thin edges indicated at 21 and 22 formed by the intersection of the concave surfaces 19 and 20 with the full width rail portion 12 become too hard and brittle and are subject to early breakage in service due to impact of the track rollers crossing the rail joint. In addition, during quenching, the thin edges frequently crack due to differences in the cooling rate between the thin sections and the adjacent thicker sections.

This difficulty has been overcome by the apparatus illustrated in Fig. 2 which comprises an endless belt 23 which is carried for rotation on a pair of power driven drums 24. The belt is adapted to carry a plurality of track links 10 at a predetermined rate between a pair of guide bars 25 which are provided to insure that the links are properly aligned with respect to the side edges of the belt. The track links are carried first through the induced heating field produced by an induction heating block 26, which is adapted to produce localized heating of the rail surface in a conventional manner. After heating, the track links are carried past a pair of fog nozzles 27 and 28 adapted to spray a mixture of air and liquid coolant on the area of the rail surface immediately adjacent the thin edges 21 and 22 only. The nozzles are calibrated to discharge coolant and air in the proper proportions to cool the area adjacent the thin edges to a predetermined temperature below the critical temperature of the material. After passing the fog nozzles, the track links pass under a quench block 30, connected by a pipe 31 to a suitable source of liquid coolant (not shown) which is sprayed on the links, quenching the entire part.

The quench block is spaced from the fog nozzles a distance sufficient to permit the pre-quenched thin edges to be reheated, by residual heat in the remainder of the link, to a drawing temperature. After quenching, the major part of the rail surface is hardened, however, the areas immediately adjacent the thin edges 21 and 22 are relatively soft due to quenching by the fog spray and subsequent reheating to a drawing temperature prior to the final quenching of the entire part. The hardness of the thin edges may be controlled by variation of their quenching temperature and amount of reheating prior to the final quench to produce the desired hardness pattern in the rail surface. In addition, by providing a softer more ductile material at the thin edges, cracking in this area is eliminated.

The fog nozzles 27 and 28 are connected by pipes 32 and 33 to a suitable source of compressed air (not shown) and also connected by pipes 34 and 35 to a tank 36 adapted to collect a part of the coolant discharged from the quench block 30. The flow of air through the nozzles withdraws coolant from the tank by aspiration which intermixes with the air stream and is discharged as a fog-like spray. The flow of air through the nozzles is controlled by normally closed poppet type valves 37 and 38 interposed in the pipes 32 and 33 respectively. The valves 37 and 38 are adapted to be opened and closed by electrically actuated solenoids 40 and 41, one of which is associated with each of the valves. The operation of the solenoids is controlled by an automatic electrically actuated timing mechanism indicated generally at 42 which is connected by electrical conductors 43 and 44 to a suitable electrical source, and to the solenoid 40 by conductors 45 and 46, and to solenoid 41 by conductors 47 and 48. The timing mechanism is adapted to be energized by a switch 59 connected therewith by conductors 51 and 52. The switch 50 is adapted to be actuated by an arm 53 extending from a shaft 54 supported for rocking movement in a pair of bearings indicated at 55. A second arm 56 is rigidly secured to the opposite end of the shaft 54 and at its extending end carries a roller 57 adapted to be engaged by a boss 58 extending from each of the track links. As the track link passes along the belt, the boss 58 engages the roller 57, depressing the arm 56 and rocking shaft 54 which closes the switch 50, energizing the electrical timing mechanism 42. After the timing mechanism has been energized, it automatically controls the operation of the valves 37 and 38 so that spray from the nozzle 27 is directed on the thin edge 22 and the spray from the nozzle 28 is directed on the thin edge 21 only. As the timing mechanism is energized by each track link as it reaches a predetermined position and operates for one cycle only, the spray from the fog nozzles may be accurately timed to occur as the thin edges reach the proper position regardless of the spacing of the track links on the belt.

As is best illustrated in Fig. 3, the timing device comprises a continuously operating synchronous motor 60, a drive shaft 61, a clutch 62, a solenoid 63 for actuating the clutch, and a drive gear 64. The gear 64 is in driving engagement with a rack bar 65 which is adapted for sliding movement in the housing enclosing the mechanism. Movement of the rack bar actuates normally open switches 66 and 67 associated with solenoids 40 and 41 respectively. Switches 66 and 67 are provided with a pair of pivotally supported lever

arms identified as 66a, 66b, 67a and 67b respectively, disposed in the path of the rack bar to effect closing and then opening of the switches in sequence. A switch 69, adapted to be closed by the solenoid 63, is disposed between conductors 51 and 52 of switch 50 to keep the solenoid energized after switch 50 is opened by the boss 58 passing beyond roller 57. A normally closed switch 71 is connected by a conductor 72 to solenoid 63 and a conductor 73 with conductor 44 to maintain an energizing current in the solenoid. The switch 71 is adapted to be opened by the rack bar at the end of the cycle, deenergizing the solenoids 63, permitting the rack bar to be returned to its starting position by a return spring 74.

In operating, closing the switch 50 energizes solenoid 63 by way of conduits 43, 51, 52, 72, 73, and 44 which in turn engages the clutch 62 and closes switch 69. Upon engagement of the clutch, the rack bar 65 is moved downwardly by gear 64 until it engages lever 66a closing switch 66. Closing of switch 66 energizes solenoid 40, by way of conduits 43, 45, 46, switch 66, and conduit 44, which in turn opens valve 37, spraying air and coolant from nozzle 27 on the thin edge section 22 of the track link. Valve 37 remains open until the rack bar 65 engages lever 66b, opening switch 66 and deenergizing solenoid 40.

Further movement of the rack bar downwardly actuates lever 67a, closing switch 67, which energizes the solenoid 41 by way of conductors 43, 47, 48, switch 67, conductors 73 and 44. Energizing solenoid 41 opens valve 38, spraying air and coolant from the nozzle 28 on the rail surface of the track link adjacent the thin edge section 21. The valve 38 remains open until the rack bar 65 engages lever 67b, opening the switch and deenergizing the solenoid 41. The rack bar 65 will continue to travel downwardly until it opens switch 71 at which time, the solenoid 63 is deenergized, disengaging the clutch 62 and the rack bar is returned to its starting position by the spring 74. The timing mechanism is conventionally adjustable to permit variation of the timing and sequence of the operation of the switches 66 and 67 to insure that the desired operation of the fog nozzles is obtained.

We claim:

1. In an apparatus for controlling the hardness pattern in an irregularly shaped article during the heat treatment thereof with localized heating and quenching means, means to advance a plurality of articles one at a time past the heating and quenching means, a plurality of fog nozzles intermediate the heating and quenching means, automatic timed control means actuated by contact of an advancing article for directing a fog-like spray through said nozzles on selected parts intermediate the leading and trailing end of the article in timed relation to its advancement, and means to discontinue said fog-like spray after treatment of said selected parts.

2. In an apparatus for controlling the hardness pattern in an irregularly shaped article during the heat treatment thereof with localized heating and quenching means, means to advance a plurality of articles one at a time past the heating and quenching means, a fog nozzle intermediate the heating and quenching means, automatic timed control means actuated by contact of an advancing article for directing a fog-like spray through said nozzles on selected parts intermediate the leading and trailing end of the article in timed relation to its advancement, and

means to discontinue said fog-like spray after treatment of said selected part.
